[57] **CLAIM**

The ornamental design for a combined neck and shoulder massager, as shown and described.

DESCRIPTION

FIG. 1 is a perspective view of a combined neck and shoulder massager, showing our new design;
FIG. 2 is a top plan view thereof;
FIG. 3 is a bottom plan view thereof;
FIG. 4 is a side elevational view thereof, the opposite side elevational view being identical thereto;
FIG. 5 is a front elevational view thereof; and,
FIG. 6 is a rear elevational view thereof.
